UNITED STATES PATENT OFFICE.

WILLIAM R. SCHWAB, OF KANSAS CITY, MISSOURI, ASSIGNOR TO THE CAMERAGRAPH COMPANY, OF KANSAS CITY, MISSOURI, A CORPORATION OF ARIZONA.

COPY-HOLDER FOR PHOTOGRAPHIC APPARATUS.

1,070,848.

Specification of Letters Patent. Patented Aug. 19, 1913.

Application filed February 1, 1913. Serial No. 745,723.

To all whom it may concern:

Be it known that I, WILLIAM R. SCHWAB, a citizen of the United States, residing at Kansas City, in the county of Jackson and 5 State of Missouri, have invented new and useful Improvements in Copy-Holders for Photographic Apparatus, of which the following is a specification.

This invention relates to improvements in 10 apparatus for making photographic reproductions of records, and more especially books and other documents, which contain writing or other matter, the present invention providing means whereby such records, 15 particularly books, may be supported and held in flat position and in the focal plane of the camera in such a manner that all of the matter on the page or sheet shall be reproduced even though such matter may extend 20 to the edge of the sheet without leaving a margin.

The present invention is adapted to be used particularly in connection with a copyholder of the general type shown and described 25 in the patent to C. J. Ellis, No. 978,719 of December 13, 1910, and in the present embodiment of the invention, the device is shown in connection with such a copyholder.

30 In the accompanying drawing:—Figure 1 is a front elevation of a copyholder provided with the record holding clips and illustrating one mode of using them; Fig. 2 represents a section through the copyholder on the line 2—2 of Fig. 1; Fig. 3 represents an 35 enlarged section on the line 3—3 of Fig. 1; Fig. 4 is a perspective view of one of the side members of the copyholder frame; Fig. 5 is a perspective view of one of the cross bars to 40 which the clips are adapted to be attached; Fig. 6 is a detail perspective view of one of the clips.

Similar parts are designated by the same reference characters in the several views.

45 The present invention is applicable generally to copyholders or record supports of various types. It is shown and will be described as applied to a copyholder of the general type disclosed in the prior patent 50 aforesaid, but it is to be understood that the invention is not limited in its application.

In the present instance, the copyholder embodies a case 1 which is supported on a standard 2 and contains a pair of followers 55 3 which are adapted to bear against the two

halves of a book and to press the same toward the front of the case, springs 4 acting upon the followers to perform this function. The front of the case is provided with a frame which carries means to press against 60 the open book and thereby position the two open pages thereof in the same plane, the equalizing springs 4 compensating for any difference in the thicknesses of the two sides of the book. This frame is preferably 65 hinged at 5 to the case or body of the copyholder in order to facilitate manipulation of the frame to permit pages of the book to be turned, as well as to permit the book to be inserted and removed. A catch 6 is provided to retain the frame in operative position. This frame embodies a pair of side members 7, each having a pair of slots 8, and a pair of cross bars 9 are provided which serve to sustain the pressure exerted on the 75 book by the equalizing springs 4. These bars are adjustable in a direction toward and from one another to enable them to accommodate books or documents of different dimensions, the cross bars having threaded 80 studs 10 which are adjustable in the slots 8 of the side members of the frame, and clamping nuts 11 serve to secure the cross bars in the different adjusted positions.

According to the present invention, clips 85 or equivalent devices are provided which are adapted to bear upon the two halves of the book to sustain the pressure exerted thereon by the equalizing springs, and these clips have fingers to engage the exposed 90 pages of the book and thereby hold them in the focal plane of the camera. These clips are adapted to coöperate with the corners of the book. In the construction shown, a set of four clips is used, these clips being 95 similar in construction. Each clip embodies a flat base 12 which is adapted to lie against the underside of the respective cross bar 9 and to project therefrom a distance sufficient to enable this bar to bear upon the 100 corner of a book, as shown in Figs. 1, 2 and 3. Each clip also has a flanged portion 13 which is adapted to partially overlie the respective cross bar, and a set-screw 14 is threaded through a collar 15 on the clip 105 and is adapted to clamp against a flange on the cross bar. Each clip is capable of being secured in any desired position longitudinally of its respective cross bar. In practice, these clips bear upon the respective cor- 110

ners of the halves of the book, the pages to be photographed, however, lying on the upper sides of the base portions of the clips. When the clips are so applied, the base portions thereof will sustain the forward pressure exerted on the two halves of the book by the equalizing springs and the exposed pages which are to be photographed will lie accurately in the same plane. The clips are provided with devices for holding the exposed pages which overlie the base portions of the clips, a resilient spring finger 16 being provided for each clip in the present instance, and this spring finger is capable of being moved to and from a position above the page or sheet. In the construction shown, each spring finger is pivoted to its respective clip by a pin 17, and the full and dotted lines in Fig. 6 show the spring finger in operative and inoperative positions, respectively.

In practice, the clips are adjusted according to the dimensions of the book or object to be held, the clips on each cross bar being adjustable toward and from one another and the cross bars are also adjustable toward and from one another. The base portions of the clips sustain the pressure of the two halves of the book and the exposed page which is to be photographed overlies the base portions and, hence, the base portions of the clips do not obscure or cover any portion of the page and the adjustable spring fingers of the clips can be set in a manner to hold the exposed pages at the corners without, however, covering any of the matter contained thereon, the spring fingers being usually adjusted to engage the extreme corners of the pages, as shown in Fig. 1.

I claim as my invention:—

1. Apparatus of the class described embodying means to contain a book or similar object, and means for holding the open pages thereof in the same plane comprising devices having portions adapted to press on the pages beneath the exposed pages, and fingers arranged to bear on the exposed pages.

50 2. Apparatus of the character described embodying book-receiving means, and devices for holding the open pages thereof in the same plane, each device having a base portion to press on the pages beneath the open page, and a finger operative to press the open page against said base portion.

55 3. Apparatus of the character described

embodying book-receiving means, and devices for holding the open pages thereof in the same plane, each device having a base portion to press on the pages beneath the open page, and a finger adjustably connected to said base portion and operative to press the open page against said base portion.

60 4. Apparatus of the character described embodying book-receiving means, and devices for holding the open pages thereof in the same plane, each device having a base portion to press on the pages beneath the open page, a resilient finger operative to press the open page against said base portion, said finger being pivoted to the base portion whereby it may swing to and from an operative position.

65 5. In apparatus of the character described, the combination of a casing to contain a book in open condition, and a set of devices adapted to coöperate with the corners of the book to hold the open pages thereof in the same plane, said devices being relatively adjustable in two directions to accommodate books of different sizes.

70 6. In apparatus of the character described, the combination of a casing to contain a book in open condition, cross bars connected to the casing and adjustable toward and from one another, and a set of devices adapted to coöperate with the corners of the book to hold the open pages thereof in the same plane, said devices being attached to and adjustable longitudinally on said cross bars.

75 7. In apparatus of the character described, the combination of a casing to contain a book in open condition, cross bars connected to the casing and adjustable toward and from one another, a set of devices adapted to coöperate with the corners of the book to hold the open pages thereof in the same plane, said devices being attached to and adjustable longitudinally on said cross bars and each having a rigid base portion to bear on the corners of the book beneath the exposed pages, and a spring finger operative to press the corners of the exposed page against the base portion.

80 In testimony whereof I have hereunto set my hand in presence of two subscribing witnesses.

WILLIAM R. SCHWAB.
